UNITED STATES PATENT OFFICE.

ROBERT ESNAULT-PELTERIE, OF PARIS, FRANCE.

THROTTLE-OPERATING MECHANISM FOR EXPLOSION MOTORS.

Application filed December 9, 1919. Serial No. 343,668.

To all whom it may concern:

Be it known that I, ROBERT ESNAULT-PELTERIE, a citizen of the French Republic, residing at 43 Boulevard Lannes, Paris, Seine, 5 in the Republic of France, have invented certain new and useful Improvement in Throttle-Operating Mechanism for Explosion Motors, of which the following is a specification.

10 This invention relates to operating mechanism for the throttle of explosion motors and more especially those of automobile vehicles.

Hitherto the operation of the throttle has 15 always been effected by a simple rod connecting the accelerating pedal or hand-lever to the operating lever of the throttle. The result is that at a slow speed a very small movement of the foot or of the hand, of 20 the driver causes a very considerable variation of the opening of the throttle and therefore an erratic behaviour of the motor. It is known in practice that when the valve of a carburetter is nearly closed, a very 25 small variation of opening occasions a very great change of admission of fuel.

In the case of automobile motors when 30 running at a slow speed all drivers know that the jolting caused by a rough and bumpy road is liable to cause by inertia, involuntary movements of the foot which bring about abrupt jerks in the running of the motor.

On the other hand even a slight movement of the pedal produces at any position 35 of the stroke a variation of opening of the throttle which is substantially constant.

The result of this is that when the 40 throttle is fully open, the inverse defect of the foregoing is produced that is, the opening for the passage of the gases is not more than feebly affected "in relative value" by the same movement of the foot, or of the hand, and the operation lacks sensitiveness.

45 The arrangement which forms the subject matter of the present invention has for its object to obviate this disadvantage by permitting at slow speed only an extremely small variation of opening for a large 50 movement of the pedal and conversely for large openings.

This invention, therefore, consists in providing means for operating the throttle of explosion motors characterized by the fact 55 that the sensitiveness of the operating

mechanism is practically constant at all speeds whereby erratic behaviour of the motor is obviated.

The accompanying drawing shows by way of example, two practical methods of carrying out the invention and will render the peculiarities and advantages thereof properly understood.

Figure 1 represents diagrammatically the ordinary known arrangement. 65

Figure 2 is a similar view showing mechanism in accordance with this invention.

The same parts are denoted by the same reference letters in Figures 1 and 2:— AE denotes the operating lever and pedal, 70 pivoted at B, AC is the rod which transmits the movement to the butterfly valve or throttle D of the carburetter.

In order to express mathematically the characteristics of these two arrangements, 75 let α be the angle which the throttle makes with its original closed position, x the movement of the pedal necessary to effect that opening and K the constant.

An ordinary operating mechanism, such 80 as that shown in Figure 1, approaches practically the condition

$$\frac{d\alpha}{dx} = K \quad (\text{Equation No. 1})$$

85 while the arrangement constructed according to the invention (see Figure 2) approaches practically

$$\frac{d\alpha}{dx} = K \quad (\text{Equation No. 2})$$

90 that is to say, in proportion as the opening of the throttle or butterfly valve increases, movements of the pedal of an amplitude dx produce greater angular movements of the 95 throttle.

The exact solution may be obtained by means of a cam control, but strict exactness is not necessary and simplicity should govern everything.

100 In the arrangement illustrated in Figure 2 the accelerator pedal E is arranged in such a way that at a low speed the operating rod AC is only slightly above the pivot B, that is to say, the levers AC and AB make a 105 small angle between them.

On acceleration, on the contrary, the rod AC is brought to the position A'C', that is, nearly at right angles to the arm AB which is then in the position A'B. 110

The lever CD which operates the throttle, on the contrary, forms at slow speed an angle of nearly 90° with the rod AC while on acceleration it forms an acute angle A' C' D.

Either of these two conditions would suffice to produce the result sought by approaching sufficiently the mathematical condition indicated.

10 It must also be understood that the mechanical arrangements may be slightly modified in order to best suit the different types of the carburetter, operating devices, etc.

15 What I claim and desire to secure by Letters Patent of the United States is:—

1. Mechanism for operating the throttle of explosion motors comprising a control pedal attached to the end of a lever, rods connecting said pedal lever to the throttle, and means for producing relatively small variations in the opening of the throttle at slow speeds, and conversely producing relatively great variations in the opening at high speed.

2. In mechanism for operating the throttle of explosion motors a rod connecting

the pedal-lever to the throttle of the carburetter so arranged that at slow speed the said rod makes with the pedal-lever a very small angle and with that of the throttle approximately, or quite, a right angle and conversely when the motor is running at high speed.

3. Mechanism for operating the throttle of explosion motors comprising an operating lever pivoted to the frame at the opposite end to which the accelerator pedal is attached and made in two portions inclined the one to the other, a rod pivoted at one end to said operating lever at the junction of the said two portions and in the position occupied at low speed forming only a very small angle with the lower portion of the operating lever and at its other end to a rod directly connected to the throttle so that it forms therewith approximately a right angle in the position occupied at low speed.

In testimony whereof he affixes his signature in presence of a witness.

ROBERT ESNAUT-PELTERIE.

Witness:

HENRY T. WILCOX.
